HAMMER FOR BODY AND FENDER WORK

Filed April 24, 1947

FIG. 1

FIG. 2

INVENTOR:

GILBERT J. INCE

BY

Warren G. E. Mitchell

ATTORNEY

UNITED STATES PATENT OFFICE

155,426

DESIGN FOR A HAMMER FOR BODY AND
FENDER WORK

Gilbert J. Ince, Greeley, Colo., assignor of seven
and one-half per cent to Wilbur A. E. Mitchell
and thirty per cent to Orville C. Winstead, both
of Greeley, Colo.

Application April 24, 1947, Serial No. 138,604

Term of patent 14 years

(Cl. D54—13)

To all whom it may concern:

Be it known that I, Gilbert J. Ince, a citizen of the United States, residing at 1107 9th Street, Greeley, in the county of Weld and State of Colorado, have invented a new, original, and ornamental Design for a Hammer for Body and Fender Work, of which the following is a specification, reference being had to the accompanying drawing, forming part thereof, in which:

Figure 1 is a plan view of a hammer for body and fender work, showing my new design; and

Figure 2 is a side view thereof.

I claim:
The ornamental design for a hammer for body and fender work, as shown.

GILBERT J. INCE.
